UNITED STATES PATENT OFFICE.

CLARENCE H. CALDWELL, OF OAK PARK, ILLINOIS.

TYPEWRITER COPYHOLDER.

Application filed June 9, 1924. Serial No. 718,692.

This invention relates to copy holders for typewriters adapted for line by line presentation of the copy.

It is an object of this invention to provide an improved copy holder adapted to present the copy to be read at substantially the same distance from the operator's eyes as the typewriter platen to obviate the necessity of change of focus of the eyes each time the operator shifts his gaze from the copy to the platen.

It is also an object of this invention to provide such a copy holder wherein the line to be copied is presented immediately over the typewriter platen to reduce the angular shift of the operator's gaze to the minimum possible without interference with the normal operation of the typewriter.

It is another object of this invention to provide a telescoping and folding copyholder attached to or built into a typewriter and adapted to fold down over the top of the typewriter into a position occupying so little extra space that such a typewriter and copy holder can be used in the space provided in an ordinary disappearing typewriter desk.

It is a further object of this invention to provide an improved copy holder mechanism adapted for a line by line presentation of copy wherein the spacing of the lines is variable in variable stepped synchronism with the ordinary typewriter spacing.

It is also an object of this invention to provide a copy holder having an improved ratchet feed mechanism together with an adjustable shielding drum adapted to be interposed between the pawl and ratchet for various fractions of the stroke of the pawl whereby the spacing will be proportionally varied.

It is also an object of this invention to provide a copy holder for typewriters adapted to shift the copy one line at a time by means of an added key on the keyboard of the typewriter.

It is still another object of this invention to provide a quickly engageable copy clamp in a device of the kind described.

It is a further object of this invention to provide a detent mechanism on the feeding mechanism whereby overrunning thereof is prevented.

Other and further important objects of this invention will be apparent from the disclosures in the specification and the accompanying drawings.

This invention (in a preferred form) is illustrated in the drawings and hereinafter more fully described.

On the drawings—

Figure 1 is a side elevation of a typewriter having a device embodying the features of this invention applied thereto, in operative position.

Figure 2 is a top plan view of the device.

Figure 3 is an enlarged section on the line 3—3 of Figure 2 showing in dotted lines the position of the copy holder when inserting copy.

Figure 4 is an enlarged section on the line 4—4 of Figure 1 showing the feeding and spacing mechanism.

Figure 5 is a fragmentary bottom view of the spacing and indexing mechanism.

Figure 6 is a section on the line 6—6 of Figure 5.

Figure 7 is a section on the line 7—7 of Figure 5.

Figure 8 is a fragmentary section on the line 8—8 of Figure 4.

Figure 9 is a fragmentary section on the line 9—9 of Figure 1.

Figure 10 is a fragmentary section on the line 10—10 of Figure 4.

Figure 11 is a section of the paper clamping device.

As shown on the drawings:

The typewriter chosen for illustrative purposes comprises the usual parts including a frame 10, roller platen 11, line spacing lever 12 and keyboard 13. When providing the device of this invention for attachment to existing typewriters an auxiliary base or bracket 14 is provided to house the operating mechanism, and preferably this bracket 95 is formed to fit and be secured to one side and rear of the typewriter frame, the side portion 15 of the bracket serving to house an operating key lever 16, pivoted at 17 and having a key 18 offset to align with the 100 standard keyboard of the typewriter.

Mounted traversely inside the back 19 of the bracket 14 is a shaft 20 having a knob 21 at one end for use in rotating it in either direction. The other end of the shaft is loosely journalled in the sleeve 22 of an adjusting knob 23 for varying the spacing of the feeding mechanism. Mounted on the shaft 20 are drums 24 and 25, the latter having longitudinal corrugations 26 on a portion of its surface adapted to be engaged by a spring detent 27 to limit the movement of

the shaft to the spacing between one or more of these corrugations. For example if the feeding mechanism moves the shaft slightly short of the detent engaging position, the 5 spring detent tends to complete the movement.

Cords 28 are wound on each drum and the free ends are attached to a paper clamp 29 comprising a strip of metal bent upwardly 10 at each end, the rectangle so formed being closed by a bar 30 hinged at one end and having a clamp 31 at the other end to engage the upstanding end of the bottom strip. Bow springs 32 are secured at their centers 15 to the bar 30, the depending free ends of the springs being adapted to press sheets of copy against the bottom strip of the clamp.

The feed mechanism proper comprises a rack 33 formed on the end of the key lever 20 16 and engaging a pinion 34 free on the shaft 20 and carrying a cam disc 35 having a spring urged pawl 36 mounted near the periphery of the disc. A ratchet wheel 37 is pinned to the shaft alongside the disc 35 and 25 a flanged disc 22^a formed integral with the adjusting knob sleeve 22 partly envelops the ratchet wheel, the flange of the disc being cut away for a portion of its circumference to expose the ratchet teeth to engagement by 30 the pawl. By rotating the adjusting knob this mutilated flange can be brought under the pawl for varying proportions of its stroke thereby permitting a pawl engagement for a movement of one or more teeth 35 spaces on the ratchet wheel. The cam surface 38 of the pawl disc is so formed that at the end of the pawl stroke the cam engages one end of a trigger 39 the other end of which is thereby forced into one of the 40 spaces of a toothed wheel 40 pinned to the shaft to positively prevent over-running of the shaft. This trigger is normally retracted by a spring 41 so that it is only brought into 45 action at the end of the pawl stroke and remains in locking engagement with the wheel 40 only until the key is released by the operator. The adjusting knob 23 carries a pointer 42 which, in connection with suitable indicia 43 on the surface of the bracket 50 around the knob, shows the adjustment of the ratchet shield for shifting one or more of the unit spaces at a single key movement.

The copy holder mounting proper comprises a hinged upstanding member 44 55 which tilts backward against a stop 45. Slidably or telescopically mounted on this member is a back plate 46 which has a paper supporting plate 47 hinged thereto at 48 and extending forwardly over the typewriter platen and paper support of the typewriter itself. At its forward end this supporting plate is preferably curved upwardly as at 49 to form a copy guide. A pair of 60 upstanding lugs 50 are mounted on this 65 plate adjacent the hinge, and a rod 51 se-

cured in these lugs forms a pivot for a plate 52 on which the clamp bar 29 slides and is held thereto by hooks 53 engaging over the edges of the plate 52. The forward edge of this plate is turned under with a radius 55 70 sufficient to provide for paper rollers 54 which prevent the copy from dragging on the surface of the plate while being pulled around the radius. This curved portion forms the copy reading surface and is located 75 as close to the platen as is convenient, and in the focal plane of the platen to eliminate eye strain in continually shifting one's gaze from the copy to the typewriting and back again. A bar 56 is pivoted from a rod 57 80 so as to lie on this surface to define the line of copy and hold the sheet of copy from bulging outwardly. The rod 57 is secured to the under surface of the plate 52 and in writing position this bar rests in forked supports 58 extending upwardly from the supporting plate.

As shown by the dotted lines of Figure 3 the upper plate may be lifted or pivoted 90 about its hinge 48 to permit ready insertion of the sheets of copy. The dotted lines of Figure 1 likewise illustrate the upward movement of both plates as a unit when it is desired to insert fresh paper in the typewriter. It will be noted that as the hinge 95 for the upper plate is fixed as to the lower plate, the relative positions of the two plates are not disturbed by such movement so that this operation has no tendency to disturb the adjustment of the copy paper. 100

Depending rearwardly from the rod 51 is a hooked member 59, the hook 60 of which engages a rod 61 secured to lugs 62 on the back plate. This hook serves to hold the entire overhanging copy holder free from the typewriter when the telescoping back is extended, to prevent interference therewith. When the members 44 and 46 are telescoped together the hook releases sufficiently to allow the overhanging part of the device to 110 fold flat on top of the typewriter. Similarly, lifting the entire overhanging portion of the copy holder allows the hook to slip along the rod.

I am aware that many changes may be 115 made, and numerous details of construction may be varied through a wide range without departing from the principles of this invention, and I therefore do not purpose 120 limiting the patent granted hereon, otherwise than necessitated by the prior art.

I claim as my invention:

1. A copy holder for typewriters comprising means for presenting copy in a position above and in close proximity to the typewriter platen, a folding and extensible support therefor, feeding mechanism for advancing said copy from line to line, means for varying the amount of feed as multiples of the unit spacing of the lines of copy, 130

and a key disposed in the keyboard of the typewriter for operating said feeding mechanism.

2. A copy holder for typewriters comprising means for presenting copy above and in the approximate vertical plane of the typewriter platen, and a telescoping and folding support therefor adapted to allow the device to be folded down over the typewriter 10 when not in use, hinges between said means and support whereby the means may be lifted away from the operative position to facilitate insertion of sheets of paper in the typewriter.
- 15 3. In a copy holder a movable paper clamp, a support over which the clamp slides, and feeding mechanism for advancing the paper clamp varying distances at a time, comprising a shaft having drums 20 thereon, cables wound on said drums and attached to said paper clamp, a ratchet wheel attached to said shaft, a pawl oscillatable over said ratchet wheel, a shield adapted to be adjustably interposed between said ratchet wheel and said pawl to limit the period of engagement thereof.
- 25 4. In a copy holder a movable paper

clamp, a support over which the clamp slides, and feeding mechanism for advancing the paper clamp varying distances at a time, comprising a shaft having drums thereon, means on said shaft limiting the movement of the surface of the drums to multiples of the typewriter line spacing, cables wound on said drums and attached to said paper clamp, a ratchet wheel attached to said shaft, a pawl oscillatable over said ratchet wheel, a shield adapted to be adjustably interposed between said ratchet wheel and said pawl to limit the period of engagement thereof. 30 35 40

5. A copy holder for typewriters including line by line feeding mechanism including a pawl, a ratchet engageable thereby for various proportions of the pawl stroke, 45 and detent mechanism operated by the feeding mechanism adapted to limit the feeding mechanism to multiples of a given unit spacing whereby overrunning of the ratchet is prevented. 50

In testimony whereof I have hereunto subscribed my name.

CLARENCE H. CALDWELL.
